CLAIM

The ornamental design for a folding ratchet, as shown and described.

DESCRIPTION

FIG. 1 is a top, front, right perspective view of a folding ratchet embodying the new design;

FIG. 2 is a top, rear, right perspective view thereof;

FIG. 3 is a bottom, rear, right perspective view thereof;

FIG. 4 is a bottom, front, right perspective view thereof;

FIG. 5 is a top view thereof;

FIG. 6 is a bottom view thereof;

FIG. 7 is a right side view thereof, the left side view being a mirror image thereof;

FIG. 8 is a front view thereof; and,

FIG. 9 is a rear view thereof.

The dash-dash broken lines are for the purpose of illustrating portions of the folding ratchet and forms no part of the claimed design.

The dot-dash broken lines represent unclaimed boundaries and form no part of the claimed design. In FIGS. 3, 4, and 6, the region on the flat underside of the ratchet between the dot-dash broken line and the adjacent interior solid line forms no part of the claimed design.
